UNITED STATES PATENT OFFICE.

CHARLES P. R. MACAULAY, OF CHICAGO, ILLINOIS.

LOGIC MACHINE.

1,079,504.

Specification of Letters Patent.

Patented Nov. 25, 1913.

Application filed July 18, 1910. Serial No. 572,550.

To all whom it may concern:

Be it known that I, CHARLES P. R. MACAULAY, subject of George V, King of Great Britain and Ireland, residing at Chicago, in the county of Cook and State of Illinois, have invented a certain new and useful Improvement in Logic Machines, of which the following is a full, clear, concise, and exact description, reference being had 10 to the accompanying drawings, forming a part of this specification.

My invention relates to logic machines in which movable elements are employed to differentiate groups of characters, denoting 15 terms of propositions, so as to exhibit logical operations; and the objects of my invention are, first, to provide means for manipulating such elements by subjecting them to an operating influence and by restricting 20 the operation of such influence on certain of such elements; and second, to provide means for disclosing the relation of propositions of the same logical import.

I shall explain my invention more fully 25 by reference to the accompanying drawings, showing the preferred embodiment thereof, in which—

Figure 1 is a plan view of the machine, parts being broken away to reveal interior 30 mechanism, other interior mechanism and certain marks thereon being shown in dotted lines; Fig. 2 is a plan view with the cover removed to show interior mechanism, certain marks on such internal mechanism being 35 omitted for the sake of clearness and certain movable parts being shown in positions different from the positions of such parts in Fig. 1; Fig. 3 is a sectional elevation on line 3 3 of Fig. 2 with the cover removed to show interior mechanism, certain marks on such internal mechanism being 40 omitted for the sake of clearness and certain movable parts being shown in positions different from the positions of such parts in Fig. 1; Fig. 4 is a sectional elevation on line 4 4 of Fig. 2 with the cover in place; Fig. 5 is a sectional elevation on line 5 5 of Fig. 2 with the cover in place; Fig. 6 is a sectional elevation on line 6 6 of Fig. 45 2 with the cover in place; Fig. 7 is a plan view in section of certain internal mechanism on line 7 7 of Fig. 8; Fig. 8 is a sectional elevation on line 8 8 of Fig. 2 with the cover in place.

Like parts are indicated by similar characters of reference throughout the different figures.

A box or casing *a'*, of any suitable material, serves to support and protect the mechanism. Sixteen character strips *b'* rest on rigidly fixed supports *c'*. These character

strips are maintained in parallel positions and are preferably separated slightly by small pins *d'* projecting from the supports, but they normally have free longitudinal 60 movement within certain limits. These longitudinal movements of the different character strips are accomplished by tilting the machine through a sufficient angle either away from or toward the operator, according to the direction in which it is desired to have the strips move, all strips free to move sliding on their supports *c'*. The position of the machine when tilted away from the operator will be referred to as its first 70 position, its horizontal position will be referred to as its second position, and its position when tilted toward the operator as its third position. I preferably rely on gravity for the movements of the character 75 strips *b'* when the machine is placed in either its first or third position, but I do not wish to be limited to this agency. On the upper face of each character strip *b'* appear three groups of characters, as shown 80 in Fig. 1, one group near each end and another near the center of the strip. The uppermost group consists of a dash, a star and a certain combination of characters distinctive of the character strip; the middle 85 group consists of a dash, the same combination of characters and a star; the third group consists of the same combination of characters and two dashes. Suitable openings *e* through the cover of the casing are 90 so positioned as to reveal one or another of the three parts of each group of characters on each character strip. When a character strip is in its "first" position, the combination of characters belonging to the uppermost group, the star of the middle group and the lowermost dash of the third group of characters on the character strip are revealed through the cover of the machine. When the character strip is in its "second" 95 position, the star of the uppermost group, the combination of characters of the middle group and a dash of the lowermost group of characters are revealed. When the character strip is in its "third" position, the dash of the uppermost, the dash of the middle and the combination of characters of the lowermost group are revealed. In Fig. 1 the character strips are shown in various positions. Counting from the left, 100 the first, second, fifth and sixth are shown in their first positions; the tenth, eleventh

and fourteenth, are shown in their second positions; the third, fourth, seventh, eighth, ninth, twelfth, thirteenth, fifteenth and sixteenth are shown in their third positions. 5 These are the three positions which character strips may assume in this form of the machine. The combinations of characters, in this form of the machine, are combinations of small and capital letters of the 10 alphabet. The combinations shown, from left to right are as follows: *abcd*, *Abcd*, *aBcd*, *ABcd*, *abCd*, *ABCd*, *aBCd*, *ABCd*, *abcD*, *AbcD*, *aBcD*, *ABCd*, *abCD*, *AbCD*, *aBCD*, *ABCD*. The character strips are called 15 by one or more of the letters marked on them. Thus the "Abcd strip" is the second strip; the "abD strips" are the ninth and thirteenth; the "Ac strips" are the second, fourth, tenth and twelfth; the "A 20 strips" are the second, fourth, sixth, eighth, tenth, twelfth, fourteenth and sixteenth strips. It will be observed that a capital and small form of the same letter never appear on the same character strip, and 25 that either the capital or the small form of each letter appears on every strip.

The longitudinal movement of each character strip *b'* is restricted by suitably located pins *f* projecting downwardly from 30 its lower face and adapted to be intercepted in their movement by suitable obstructions. The uppermost position of each character strip *b'* is determined by a pin *f* so located as to be intercepted in its upward movement 35 by the support *c'*, this position, so determined, being the "first" position of the character strip, above referred to; and, similarly, the lowermost or "third" position of each character strip *b'* is determined 40 by another pin *f* so located as to be intercepted in its downward movement by the lower support *c'*. The intermediate or "second" position of the character strip is determined in a manner hereinafter 45 described. Various other pins *f*, as well as those above mentioned, normally have free 50 passage through open spaces *g* in the top edges of eight slides *h* and a ninth slide *o*, adapted to move close below and crosswise 55 of the character strips *b'*. These slides *h* are supported and guided by openings in the left hand side of the casing *a'* and in the support *i* near the right hand side of the casing. Their extreme movement toward 60 the left is limited by the striking of stops *h'*, which project upwardly from their right hand ends and are intercepted by the support *i*. Their extreme movement toward the right is limited by the striking of said 65 stops *h'* against the bar *k*, which is free to move to the right until it strikes the stops *l*. This bar *k* is maintained parallel to the character strips *b'* by means of connecting links *m*. The slides *h* are adapted to be moved individually to their extreme right

hand positions by pressing on their left hand ends, which protrude through openings in the left hand side of the casing *a'* so as to be accessible. They are adapted to be moved simultaneously to their extreme 70 left hand positions by pressing on the projection *k'* of the parallel bar *k*, said projection *k'* protruding through an opening in the right hand side of the casing *a'* so as to be accessible. When a slide *h* is in its extreme left hand position, it is said to be in its first position, and when it is in its extreme right hand position, it is said to be in its second position. 75

On the cover of the machine *a'* and on 80 the left hand side thereof are certain letters adapted to identify the slides *h*, as shown in Fig. 1. The first or uppermost slide is called "subject *a* slide" or "predicate *A* slide"; the second slide is called 85 "subject *A* slide" or "predicate *a* slide"; the third, "subject *b* slide" or "predicate *B* slide", etc.

In Fig. 3 is shown a sectional elevation 90 of the first or uppermost slide (called subject *a* slide). In Fig. 5 is shown a sectional elevation of the eighth slide (subject *D* slide). In Fig. 4 is shown a sectional elevation of the fifth slide (subject *c* slide). The second, third, fourth, sixth and seventh 95 slides *h* have projections *n* and open spaces *g* arranged in a manner similar to that in which the projections *n* and open spaces *g* of the fifth slide are arranged.

The parts described are so relatively arranged that when the slides *h* are in their first positions, their open spaces *g* will be in alinement with the pins *f* of the character strips, thereby permitting free longitudinal movement of the character strips *b'*, but when any one of the slides *h* is pressed into its second position, its projections *n* will intercept pins *f* of those eight of the character strips that have combinations of 100 characters marked thereon that do not contain the subject letter of the slide *h* that may be pressed into its second position, (or to state the matter otherwise, those character strips that have combinations of characters that do contain the predicate letter of 105 the slide *h* that is pressed into its second position)—which will be readily seen on comparing Figs. 1 and 2. Thus, if the third slide (subject *b* slide, or as it may also be called, predicate *B* slide) is pressed into its 110 second position, a pin *f* of the third, fourth, seventh, eighth, eleventh, twelfth, fifteenth and sixteenth character strips *b'* will be intercepted to prevent movement of said character strips from their first positions, and 115 these character strips are the *aBcd*, *ABcd*, *aBCd*, *ABCd*, *aBcD*, *ABCd*, *aBCD* and *ABCD* character strips, none of which contains the subject letter *b* of the slide pressed. 120 and all of which contain the predicate let- 125 ter *b* of the slide pressed.

ter B of said slide. The other eighth character strips have combinations of characters containing the subject letter *b* of said slide and have no pins *f* that can be intercepted by the projections of the subject *b* slide.

If two slides are pressed, one being the subject small form of any letter and the other being the subject large form of the same letter, say, subject *b* and subject *B*, and the machine is put into its third position, there will be no movement of the character strips, because the first of these two slides will lock in the first position all the character strips that do not contain the 10 small form of the letter (that is all those that do contain the large form of the letter) and the second of the two slides will lock in the first position all the character strips that do not contain the large form of the 15 letter (that is all those that do contain the small form of the letter), and as every character strip contains either the small or the large form of every letter, it follows that all the character strips will be locked in the 20 first position.

If two or more slides are pressed, no two of which are the subject small form and the subject large form of the same letter, say, subject *A*, subject *b*, subject *C* and subject *d*, 25 slides, and the machine is then put into its third position, it is obvious that the character strips that do not contain *A*, and those that do not contain *b*, and those that do not contain *C* and those that do not contain *d* (that is all those that contain *a*, *B*, *c* or *D*) are locked in the first position, and the character strip that contains *A*, *b*, *C* and *d*, that is the *AbCd* character strip is the only one not locked and it falls to the third 30 position. It will now be seen that when slides are pressed and the machine is put into its third position, those character strips that contain combinations of characters which contain all the subject letters of the 35 slides pressed, fall into the third position, and the character strips that contain any one or more of the predicate letters of the slides pressed remain in the first position; provided, however, that no two of the slides 40 pressed are the subject small form and subject large form of the same letter.

A ninth slide *o*, having projections *n* and open spaces *g* similar to those of the slides *h*, has an extreme left hand position in 45 which its open spaces are in alinement with the pins *f* and an extreme right hand position in which its projections are in alinement with the pins *f*. The extreme left hand position of the slide *o* is called its first position and is determined by its shoulder *o'* coming in contact with the left hand end of the casing *a'* and its extreme right hand position, called its second position, is determined by its shoulder *o''* coming in contact with the support *i*. The distance be-

tween any two slides *h* is substantially equal to the extreme longitudinal travel of the character strips *b'*, as above described; the projections *n*, however, of the slide *o* are at substantially five-ninths of the above mentioned distance below the lowermost slide *h*.

When the slide *o* is in its first position, the character strips may fall from the first to the third position, or vice versa, because their lowermost pins *f* pass through the open spaces of the slide *o*, but when the slide *o* is pressed into its second position, then character strips falling from the first toward the third position are arrested in the second position, because their lowermost pegs *f* 70 strike the projections *n* of the slide *o*; and, moreover, when the slide *o* is pressed into its second position, those character strips, that may have previously fallen into their third positions, are locked in the third position and cannot slide back into their first positions, when the machine is placed into its first position (sloping away from the operator), because the lowermost pins of such character strips are obstructed in their movement by the projections *n* of the slide *o*. The slide *o* may be restored from its second 75 to its first position by pressure on that part of it that protrudes from the right of the casing *a'* so as to be accessible.

The chief purpose of the slide *o* is to enable the operator to select certain combinations from those appearing in the consistent row of openings and to cause them to appear in the special row of openings for 80 inspection and then to restore them to the consistent row of openings. Suppose that combinations containing *C* are, with others, in the consistent row of openings, and it is desired to examine the combinations containing *C*. The slide *o* is pressed into its 85 second position and subject *C* slide is pressed, and the machine is put into its third position. All the combinations containing *C* (the subject letter of the slide 90 *o*) that were in the consistent row of openings will disappear therefrom (their places being taken by stars to denote that the absence of such combinations is only temporary) and those combinations will appear in the special row of openings. These 95 combinations having been inspected, the machine is put into its first position, whereupon the combinations disappear from the special and reappear in the consistent openings. If the projection *k'* is now pressed, the subject *C* slide will be restored to its first position. A plan view of the slide *o* and of the two 100 letter slides above it, is shown in Fig. 7. The various marks on the character strips 105 *b'* are not shown in Fig. 2, in order that the positions of the pegs *f* on the several strips may be the more easily seen. On the cover of the machine *a'* (Fig. 1), the letter *X* identifies the slide *o* where it protrudes from 110 115 120 125 130

the left of the machine, the letter Y identifies the slide *o* where it protrudes from the right of the machine, and the letter Z identifies the projection *k'* of the parallel bar *k* where it protrudes from the right of the machine.

5 An operation called "rectifying" the machine, consists in pressing the keys Y and Z, placing the machine into the first and then into its second position (horizontal). The result of this operation is to cause the slide *o* and all the slides *h* and all the character strips *b'* to assume their first positions.

10 The machine when so constructed, can be used in the investigation of logical inferences and in the analysis of propositions. The method of using the machine for such purposes will depend upon the nature of the matter under investigation, and I shall proceed to show how the machine may be used in certain cases, by way of illustration.

15 The capital letters A, B, C, and D may be used to denote the positive aspects of terms of propositions, and the small letters *a*, *b*, *c*, and *d* may be used to denote the negative aspects of said terms, respectively. So that if, for instance, A is taken to denote gold, then *a* will denote whatever is not gold. The letters may be made to denote not only things, but also qualities, the truth of propositions, or any circumstances whatever. A combination of letters on any character strip denotes the possibility of combining the things, qualities, etc., that may be represented by the letters of the combination. Thus if A denotes gold and B denotes metal, then the combination AB denotes that it is possible that some gold is metal, or it is possible that some metal is gold; the combination Ab denotes that it is possible that some gold is not metal, or that it is possible that something that is not metal is gold; the combination aB denotes that it is possible that something that is not gold is metal, or that some metal is possibly not gold; the combination ab denotes that it is possible that something that is not gold is not metal, or that it is possible that something that is not metal is not gold. In the same manner 20 significance may be given to combinations of three or four letters. The combinations appearing in the openings marked "Consistent" denote circumstances that are possible, and when combinations appear in the 25 openings marked "Inconsistent," they denote circumstances that are impossible. Combinations in the openings marked "Special" are combinations selected from the consistent combinations.

30 When all the character strips are in their first positions, the combinations of characters shown in the consistent openings denote all combinations of the four terms, A, B, C and D and their negatives that can possibly occur. If but three terms are involved

35 in the matter under investigation, the "D" character strips, the last eight, can be eliminated by pressing subject D slide, putting machine into its third and then back to its second position and pressing the key Z. The effect of this operation is to retain in 70 the first position the *d* character strips, the first eight, and to cause the D character strips, the last eight, to move to their third position. Thereafter the character *d*, appearing in the first eight character combinations may be disregarded, and those eight combinations will be all the combinations of the three terms, A, B and C and their 75 negatives that can possibly occur. Similarly, if but two terms are involved in the matter under investigation, after eliminating the D combinations, as above, the C combinations (the fifth, sixth, seventh and eighth) remaining in the first position, may 80 be eliminated by pressing subject C slide, putting the machine into its third and then back into its second position and pressing the key Z. All the C, as well as the D combinations will then be in the inconsistent position, and the only combinations remaining 85 in the first or consistent position will be the first four, and those four will be all the combinations of the two terms A and B and their negatives that can possibly occur and 90 the characters *c* and *d* appearing in the first four combinations may thereafter be disregarded.

95 A universal proposition is impressed on the machine by pressing appropriate slides, 100 while the machine is in its second (horizontal) position, then putting the machine into its third position, (whereupon the character strips that bear combinations that denote what is impossible, untrue, etc. move 105 to their third positions), then returning the machine to its second position and pressing the key Z, the effect of pressing the key Z being to restore to their first positions the slides that were pressed.

110 Subject letters of slides pressed are deemed connected by the conjunctive "and," while predicate letters of slides pressed are deemed connected by the disjunctive "or."

115 Universal propositions may be stated in different forms and the manner of impressing propositions of representative types will now be explained.

120 A proposition stating that a certain combination of terms is impossible is impressed on the machine by pressing slides the subject letters of which form the combination alleged to be impossible. Thus, to impress on the machine the proposition, "Whatever is A and B and *c* (not C) is impossible," 125 the slides to be pressed are the second, fourth and fifth, the subject letters of which are respectively A, B and *c*. When the machine is put into its third position, the character strips that bear combinations contain- 130

ing all the subject characters of slides pressed will, as above explained, move to their third positions, and, therefore, in this case the ABC character strips move to their third positions, as required by the proposition.

A proposition stating that no combination of characters is possible unless it contains one or others of certain characters, or in other words, that every possible combination of characters must contain one or others of certain characters, is impressed on the machine by pressing slides the predicate characters of which are the characters the presence of one or more of which is alleged to be necessary. Thus, to impress on the machine the proposition "Everything is a (not A) or b (not B) or C ", the slides to be pressed are the second, fourth and fifth, the predicate letters of which are respectively, a , b and C . When the machine is put into its third position, the character strips that bear combinations containing any one or more of the predicate letters of slides pressed, will, as above explained, be retained in their first positions, and, therefore, in this case, all the character strips that bear combinations of characters containing a , b or C will remain in their first positions, signifying that all combinations of characters that are possible contain a , b or C , as required by the proposition. It will be observed that the slides pressed are the same as the slides pressed in the preceding paragraph. The subject letters of the slides are respectively A , B and c , and, therefore, when the machine is put into its third position, the ABC character strips, denoting a combination of terms inconsistent with the proposition of this paragraph, move to their third positions. Upon consideration it will be seen that the proposition of this paragraph is of the same logical import as the proposition of the preceding paragraph.

To impress a proposition of the form " A is C ", the slides to be pressed are the second, the subject letter of which is A , (that being the subject of the proposition) and the fifth slide, the predicate character of which is C , (that being the predicate of the proposition). The subject letters of these two slides being A and c , the Ac combinations, which are inconsistent with the proposition, move to their third positions. Similarly, to impress a proposition such as, " A is b (not B)", the slides to be pressed are the second, the subject letter of which is A , and the fourth, the predicate letter of which is b . The subject letters of these two slides are A and B , and, therefore, the character strips bearing combinations containing both A and B , being inconsistent with this proposition, move to their third positions.

A proposition of the form "Whatever is A and B is C " is impressed on the machine

by pressing the second slide, the subject letter of which is A , and the fourth slide, the subject letter of which is B and the fifth slide, the predicate letter of which is C . The subject letters of the three slides being A , B and c , the ABC character strips, which denote inconsistent cases, will move to their third positions when the machine is put into its third position.

A proposition of the form, " A is B or C ", is impressed on the machine by pressing the second slide, the subject letter of which is A , and the third slide, the predicate letter of which is B , and the fifth slide, the predicate letter of which is C . The subject letters of the three slides being A , b and c , the Abc combinations, which are inconsistent with the proposition, move to their third positions, when the machine is put into its third position.

A proposition of the form "Whatever is A and B is C or D ", is impressed on the machine by pressing the second slide, the subject letter of which is A , and the fourth slide, the subject letter of which is B , and the fifth slide, the predicate letter of which is C , and the seventh slide, the predicate letter of which is D . The subject letters of the four slides pressed are A , B , c , and d , and, therefore the $ABcd$ combination, which is inconsistent with the proposition, will, when the machine is put into its third position, move to its third or inconsistent position.

A universal proposition that cannot be stated in one or other of the above forms, will on investigation be found to be a combination of one or more propositions, each of which is capable of being stated in one or other of such forms. Compound propositions of this kind are impressed on the machine by impressing successively the propositions of which they are composed. Thus, the proposition, " A is identical with B ", means " A is B ", and " B is A ". The proposition, " A is B and C ", means " A is B " and " A is C ". The proposition, " A is B or C , but not both", means, " A is B or C ", and " A is b (not B) or c (not C)". The proposition, " A or B , whichever is considered, is C ", means " A is C " and " B is C ". Compound propositions of other types may similarly be reduced to two or more propositions, each of which in effect asserts that some combination of characters is impossible, and may be impressed on the machine as above shown.

Particular propositions in effect assert that some combination of characters, appearing in the consistent openings, denote cases that are not merely possible, but are true. To impress a particular proposition on the machine, the key X (the projecting part of the slide o on the left hand side of the machine) is pressed and then slides are pressed, the subject letters of which denote the terms,

both of the subject and of the predicate, of the particular proposition, and then the machine is put into its third position, whereupon the combinations asserted by the proposition to be true will be caused to appear in the special openings. Thus, to impress on the machine the proposition, "Some A is B," press the key X and the second slide, the subject letter of which is A, and the fourth slide, the subject letter of which is B, and then put the machine into its third position. The character strips that bear combinations that contain both A and B, that is the AB character strips are the only ones that can move from the first position, but they cannot reach the third position, because their lowermost pegs f are intercepted by the projections of the slide o , and said character strips are therefore arrested in the second position, and the AB combinations will appear in the special openings. The Ab combinations (denoting that some A may be not B) and the aB combinations, (denoting that some B may be not A) remain with others in the consistent openings, as is required by the proposition.

Conclusions may be drawn from several propositions, as follows: Impress the propositions successively on the machine. The combinations remaining in the consistent openings represent all cases that are consistent with all the propositions. The conditions under which any letter or combination of letters can occur will then be seen. Thus, if it is observed that whenever A occurs, B also occurs, the inference may be drawn that all A is B, because the fact that the combination Ab (denoting that some A may be not B) does not appear in the consistent openings shows that that combination cannot be true. Again, if it is observed, for instance, that the combination AB always occurs with C, but in one case combined with D, and in another case combined with d, the inference may be drawn that whatever is A and B is C, but may be D or not D.

The examination of the consistent combinations may be facilitated by pressing the key X and then the slide, the subject letter of which is the character in regard to which it is desired to draw inferences and then putting the machine into its third position. All the combinations that are in the consistent openings that contain that letter will then appear in the special openings. When they have been inspected, the machine is put into its first positions, whereupon the said combinations will return to the consistent openings. If it is desired to ascertain what inferences may be drawn in regard to a combination of characters, the slides, the subject letters of which form the combination are pressed, and when the machine is put into its third positions, the character strips bearing

that combination of characters will move to the second position, and the combinations will appear in the special openings.

When, one of a series of propositions is a "particular" proposition, the "particular" proposition is impressed on the machine last.

Suppose the following problem: Four hunters, A, B, C and D, occupied a camp in different ways for seven days. (1) On days when A hunted B did not. (2) On days when B hunted, D also hunted, but C did not. (3) On days when D hunted, A or B hunted. How did they dispose themselves during the week? On how many days did D hunt and with whom?

Let A denote any day on which A hunted and let a denote any day on which he did not hunt. Let similar meanings be given to the other letters. The proposition marked (2) is equivalent to the two propositions: (2^a) When B hunted, D hunted, and (2^b) when B hunted C did not. The propositions may be stated symbolically thus: (1) A is b . (2^a) B is D. (2^b) B is c. (3) D is A or B. Rectify the machine. (1) Press subject A and predicate b slides; put machine into the third and then into the second position and then press the key Z. (2^a) Press subject B and predicate D slides; put machine into the third and then into the second position and press Z. (2^b) Press subject B and predicate c ; put machine into the third and then into the second position and press Z. (3) Press subject D and predicate A and predicate B slides; put machine into the third and then into the second position and press Z. The following combinations remain in the consistent openings:

abcd—showing that on one day none of them hunted.

Abcd—showing that on one day A hunted alone.

abCd—showing that on one day C alone hunted.

ABCd—showing that on one day A and C hunted and B and D did not.

AhcD—showing that on one day A and D hunted and B and C did not.

aBcD—showing that on one day B and D hunted and A and C did not.

AbcD—showing that on one day A, C and D hunted and B did not.

The combinations denoting cases in which D hunted may be selected from the others and caused to appear in the special openings by pressing the key X and subject D slide and putting the machine into the third position. The combinations containing D, that is, AbcD, aBcD, and AbCD, appear in the special openings. (The appearance of the machine at this point is shown in Fig. 1). It is apparent that D hunted on three days as shown in these combinations.

The sets of characters used to identify the slides protruding from the left side of the machine, may also be usefully employed to disclose propositions having the same logical import as a given proposition. As shown above, a proposition is impressed on the machine by pressing certain of the slides. When the slides are pressed, they may be read in various ways, according to the char-

acters used to identify the slides, and thus propositions of the same logical import may be discovered. Thus, in order to impress on the machine the proposition, "A case 5 where A and D are present, is a case where B or C is present," the slides to be pressed are the second, the subject letter of which is A; the eighth, the subject letter of which is D; the third, the predicate letter of which 10 is B; and the fifth, the predicate letter of which is C. The subject letters of these slides are respectively: A, D, b, c. The predicate letters of the slides are respectively: a, d, B, C. Any one or more of the 15 slides pressed may now be taken as subject slides, and the rest, if any, of the slides pressed may be taken as predicate slides, or all the slides pressed may be taken as subject slides, or all of them may be taken 20 as predicate slides. In the present case, if all the slides are taken as subject slides we have the proposition, "A case where A and D are present and B and C are absent, is impossible." If all the slides are taken as 25 predicate slides, we have the proposition, "In every case A is absent, or D is absent, or B is present, or C is present," or, if for instance, we take subject D and subject c and predicate a and predicate B, we form 30 the proposition, "A case where D is present and C absent, is a case where A is absent or B is present." Upon consideration it will be seen that if the original proposition be true, then these others (and more that may 35 be formed in a similar manner) must also be true.

While I have herein shown and particularly described the preferred embodiment of my invention, I do not wish to be limited 40 to the precise details of construction shown, as changes may readily be made without departing from the spirit of my invention, but,

Having thus described my invention, I claim as new and desire to secure by Letters 45 Patent the following:

1. A plurality of character strips each having symbols thereupon to represent terms of propositions; a casing in which these character strips are slidably mounted 50 and in which the character strips are free to be moved in opposite directions by the force of gravity acting thereupon when the casing is suitably tilted; and means for restricting movement of selected character 55 strips while permitting other character

strips to slide when the casing is tilted, said casing having openings therein at each of which a symbol appears and which symbols are changed by manipulation of the casing to cause the character strips to slide. 60

2. A plurality of character strips each having symbols thereupon to represent terms of propositions; a casing in which these character strips are slidably mounted and in which the character strips are free to be moved in opposite directions by the force of gravity acting thereupon when the casing is suitably tilted; means for restricting movement of selected character strips while permitting other character strips to 65 slide when the casing is tilted, said casing having openings therein at each of which a symbol appears and which symbols are changed by manipulation of the casing to cause the character strips to slide; and 70 means for differentiating groups of character strips and the symbols borne thereby. 75

3. A device for exhibiting logical operations, including a plurality of movably mounted character strips carrying symbols 80 related in pairs; means for restricting the movements of said character strips to effect different combinations of said symbols, each combination containing one, but not both, of the members of every pair of related symbols; and means for applying, collectively, 85 to the character strips carrying combinations containing any given symbol, restrictions against operation.

4. In a device for ascertaining propositions of the same logical import, a plurality of movably mounted character strips carrying a series of symbols related in pairs; a second plurality of movably mounted character strips carrying a second series of the 95 same symbols, in which each symbol of the first series is transposed with its related symbol; means for applying restrictions against operation to character strips and a table formed of the two series, so that each 100 symbol of one series is collocated with its related symbol in the other series.

In witness whereof, I hereunto subscribe my name this fourteenth day of July A. D., 1910.

CHARLES P. R. MACAULAY.
